UNITED STATES PATENT OFFICE

EDWARD A. PURNELL, OF YOUNGSTOWN, OHIO, ASSIGNOR TO THE GENERAL FIRE-PROOFING COMPANY, OF YOUNGSTOWN, OHIO, A CORPORATION OF OHIO

DESIGN FOR A TABLE

Application filed March 19, 1931. Serial No. 39,164. Term of patent 14 years.

To all whom it may concern:

Be it known that I, EDWARD A. PURNELL, a citizen of the United States, residing at Youngstown, in the county of Mahoning and State of Ohio, have invented a new, original, and ornamental Design for Tables, of which the following is a specification, reference being had to the accompanying drawings, forming part thereof:—

Figure 1 is a front elevation of a table, showing my new design.

Figure 2 is a rear view of a table, showing my new design.

Figure 3 is a perspective view of the table shown in Figures 1 and 2.

I claim:

The ornamental design for a table, as shown.

EDWARD A. PURNELL.
